UNITED STATES PATENT OFFICE.

JOSEPH ALBERT HARDIN, OF ANNISTON, ALABAMA, ASSIGNOR TO INTERSTATE ROOFING & FOUNDRY COMPANY, OF ANNISTON, ALABAMA, A CORPORATION OF ALABAMA.

PERMANENT MOLD.

1,019,248.

Specification of Letters Patent.

Patented Mar. 5, 1912.

Application filed October 28, 1911. Serial No. 657,322.

To all whom it may concern:

Be it known that I, JOSEPH ALBERT HARDIN, a citizen of the United States of America, residing at Anniston, in the county 5 of Calhoun and State of Alabama, have invented certain new and useful Improvements in Permanent Molds, of which the following is a specification.

My invention relates to an improved 10 means for molding andirons and other like castings in a permanent mold instead of by means of sand molds, whereby I greatly reduce the cost of production of such articles principally by reason of the fact that the 15 permanent or chill molds can be operated by common labor while sand molding requires skilled labor.

My invention has a particular advantage 20 in the manufacture of andirons, fire dogs, and like shapes of castings in that it is possible to make them in one piece and substantially free from sand or blow-holes, producing clean and sharp castings and avoiding the expense of rattling same.

25 One feature of my present invention resides in the provision of means to properly center the two sections of the cope which contain the mold cavity for one portion of the casting.

30 Another feature of my invention is the novel arrangement of gating the mold, which consists in forming a separate gate in the cope which connects with the mold cavity in the cope and does not discharge the 35 metal directly into the mold cavity in the drag, which would result in burning the mold and disfiguring the casting.

In accordance with the requirements of 40 law, I have illustrated what I regard as the preferred embodiment of my invention, but I do not desire to be limited thereto. These embodiments are illustrated in the accompanying drawings, wherein:—

Figure 1 presents a plan view of the permanent mold with the cope sections opened out in a horizontal plane. Fig. 2 is a side elevation of the permanent mold in assembled position, and Fig. 3 is an end elevation of Fig. 2. Fig. 4 is a side elevation of the permanent mold with a modified arrangement for dividing the cope.

Similar reference numerals refer to similar parts throughout the drawings.

According to the illustrations, my apparatus 55 comprises a metallic base plate or drag 1

having formed in the upper face thereof the mold cavity 2 which conforms to the design intended to be given to the front of the andiron, which is the particular casting in connection with which I have illustrated my invention. 60

Referring to Figs. 1 to 3, I illustrate the cope as formed of two sections 3 and 4 which equally divide the cope in a vertical longitudinal plane taken centrally through the 65 mold cavity 2 in the drag and each of these cope sections are shown provided with flanges 5 which are formed integral therewith or attached thereto by cap screws. Each of these flanges 5 is provided with an eye at its 70 lower end to receive a pivot bolt 6, one of which is disposed along each side of the drag with its center line level with the top face of the drag. The bolts 6 pass through lugs 7 which are formed integral with or 75 bolted to the sides of the drag and are provided at their upper ends with openings for the pivot bolt 6. On the cope section 3 there is a lug or projection 8 at its left hand end (Fig. 2), and its right hand end is provided 80 with a cover plate 9 which is adapted to cover the portion of the drag not covered by the cope sections 3 and 4, it being noted, in view of the relatively small size of the shank to be molded in the cope, these sections are 85 made smaller than the drag. Portions 8 and 9, carried by the cope sections 3, receive between them the cope section 4 and accurately 90 centers the cope sections in proper relationship in which they are adapted to be locked by the bail 10 which is pivoted to the section 3 and adapted to swing over the curved top 95 portions of the cope sections 3 and 4 and to engage the tapering wall of section 4. The cope sections 3 and 4 between them form a 100 mold cavity 11 in which the shank of the andirons is cast. I have shown each cope section provided with an oppositely disposed portion of the mold cavity 11, the lower end of which cavity, when the cope is in operating position, stands above the central portion 12 of the mold cavity 2. The top portion of 11 is angled off at 13 to provide for the inner leg or the shank of the andiron. The metal is adapted to be introduced into 105 the permanent mold in any suitable manner for best distributing it throughout the angularly disposed portions of the complete mold.

I have shown the cope sections cut away at 110

14 to form a pouring opening through which I pour metal into the gate 15 which has a branch 16 leading to the mold 11 while the lower end of the gate 15 delivers the metal 5 to a gate 17 formed in the drag and leading to the portion 12 of the mold cavity therein. Other arrangements for gating the apparatus may be used if desired, but I have found this to be the most practical way since the 10 molten metal as it is poured into the mold will not fall directly into the mold cavity in the drag but instead will fall into the groove or channel 17 which leads into the mold cavity 12. By this means I prevent the molten 15 metal from burning the mold proper and disfiguring the ornamental face of the casting.

In Fig. 4 the drag 1^a is equipped at its ends with bearing flanges 18 for the pivot bolts 19 to which cope sections 20 and 21 are pivotally connected by lugs 22 through which the pivot bolts 19 pass. It will be noted in this construction that the cope sections are divided on a transverse vertical 25 plane taken centrally through the main mold cavity 23 of the shank and at right angles to the plane on which the sections are divided in Fig. 3, it being noted that the portion of the mold 24, forming the inner 30 leg of the shank, is struck on an arc from the adjacent pin 19 as a center, to permit the cope section 20 to swing freely on its hinges in clearing the finished casting. In this construction, if desired, the pouring can be 35 effected through gate 25. If desired the mold cavity in the cope section 24 may be vented through a curved vent opening 25^a which is struck on an arc from the pivot point of the cope section so that the metal 40 therein will not interfere with the opening up of the cope sections. These are held together by a loop 10^a, similar to the loop 10, and are held against lateral displacement by side lugs 5^a.

45 In operation, the mold is assembled and locked, as shown in Figs. 2 and 3, and metal is poured through the gate 14 and flowing through the gates 15, 16 and 17, enters the mold cavity at different points and fills 50 same to form an integral andiron or fire dog. The metal mold chills the casting quickly, leaving it clean and free of blow-holes. The bail is thrown back to unlock

the cope sections, which, by reason of the manner in which they are attached to the drag, will move outwardly without binding in the casting, leaving the shank of the latter standing clear with the integral front of the andiron in the mold cavity 2 in the drag. As soon as the casting has been removed and the cope sections again clamped together, the mold is ready for another pouring and may be used in this manner continuously to produce the most marked improvement in the economical production 65 of andirons and like articles.

As hereinbefore stated the cope sections may be attached to the drag in any other suitable manner to give them the proper relative movement for the casting in the mold.

Having thus described my invention, what I claim as new and desire to secure by Letters Patent, is:—

1. In a permanent mold, a drag having a mold cavity formed therein, a multi-parted 75 cope adjustably attached to the drag, there being a mold cavity formed wholly in the cope and between the parts thereof which coincides with a mold cavity formed between the cope and drag, means to connect 80 the cope sections to the drag, to adapt them to swing clear of the finished casting, and a gate for the molten metal formed partly in the cope and partly in the drag, substantially as described.

2. A permanent mold comprising a drag, a sectional cope, there being a horizontal mold cavity in the drag and a vertical mold cavity in the cope, the cope sections being parted in a plane intersecting the vertical 90 cavity, means to hinge the cope sections to the drag at points where said sections will swing clear of the castings when swung outwardly on their hinges and a gate formed in the cope and connected by a branch passage 95 with the upper end of the mold cavity in the cope, said gate terminating in a channel formed in the drag and leading to the mold cavity therein, substantially as described.

In testimony whereof I affix my signature 100 in presence of two witnesses.

JOSEPH ALBERT HARDIN.
